TWIN ROCKER AND ROTATING TOY DEVICE

Alexander Szabo, Linden, N. J.

Application July 23, 1937, Serial No. 155,196

6 Claims. (Cl. 272—54)

This invention relates to new and useful improvements in a twin rocker and rotating toy device.

The invention has for an object the construction of a device as mentioned to be characterized by a body for supporting a see-saw board, and a rotary device mounted upon said body and adapted to be rotated in one direction by a novel means when the see-saw board which is pivotally mounted on said body is rocked up and down.

Still further the invention proposes to characterize the driving means for the rotary device by drums mounted on a vertical shaft connected with the device, and cords wound on said drums in opposite directions and connected with oppositely disposed arms associated with each other in a particular manner.

Still further the invention proposes an arrangement by which the positions of the levers may be varied for varying the speed with which the rotary device is driven as the see-saw is rocked.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a plan view of a device constructed according to this invention.

Fig. 2 is a sectional elevational view of Fig. 1.

Fig. 3 is an end elevational view of Fig. 2 looking in the direction of the line 3—3 thereof.

Fig. 4 is a fragmentary enlarged sectional view taken on the line 4—4 of Fig. 1.

Fig. 5 is a sectional view taken on the line 5—5 of Fig. 4.

Fig. 6 is a view similar to Fig. 4 but illustrating the condition of the device with the see-saw board rocked in the opposite direction.

Fig. 7 is a horizontal sectional view taken on the line 7—7 of Fig. 5.

Fig. 8 is a horizontal sectional view taken on the line 8—8 of Fig. 4.

Fig. 9 is a horizontal sectional view taken on the line 9—9 of Fig. 4.

Fig. 10 is a sectional view taken on the line 10—10 of Fig. 5.

Fig. 11 is a sectional view taken on the line 11—11 of Fig. 6.

The twin rocker and rotary toy device, according to this invention, comprises a body 10 for supporting a see-saw board 11. This see-saw

board is pivotally mounted on the body by a trunnion 12. This trunnion 12 is supported on a pair of spaced angle irons 13^a and 13^b (see Fig. 10) which are mounted on a partition 14 supported within the body 10. The see-saw board 11 may pivot one way or the other, as indicated by the dot and dash lines in Fig. 2 and the full lines in Figs. 4 and 6.

The outer ends of the see-saw board 11 are provided with seat members 15 upon which children may sit. These seat members are held fixed in adjusted positions by clamps 16 so that they may be moved inwards or outwards to properly counterbalance the see-saw board for children of different weights. Each seat structure 15 has 15 a head portion 15^a representing a horse's head and a transverse bar 15^b engaged through the head and providing handles by which a child may hold on.

A rotary device 17 is mounted on the top of the body 10. This rotary device comprises an annular ring 17^a supported by several spokes 18 arranged within the body 10 and connected with a common hub 19 fixedly mounted on a tubular drive shaft 20. This tubular drive shaft is rotatable on a stationary supporting shaft 21. The upper end of the stationary shaft 21 is provided with a flange member 22 which supports a central stationary disc 23 arranged within the annular movable member 17^a. Upon this stationary disc 23 there is a flag pedestal 24 which supports a flag post 25 on which there is a flag 26. A plurality of small figures 27^a, 27^b, etc., are mounted on the annular member 17^a (see Fig. 4) and are adapted to move when the rotary device operates.

The body 10 comprises a hollow structure supported on legs 10^a which may be mounted on the ground. On diametrically opposite sides the body 10 is provided with openings 10^b through which the see-saw board 11 extends. Above each of these openings there is a door 10^c which may be opened to give access to the interior parts which drive the rotary device.

The driving mechanism for the rotary device includes several blocks 30 which are adjustably mounted on a partition 31 mounted within the body 10. This partition is formed with slots 32 through which clamp bolts 33 pass. These clamp bolts are connected with the blocks 30 and are adapted to hold the blocks fixed. The partitions 14 and 31 are connected together by stationary braces 34. These braces 34 have cutout areas 34^a into which portions of the blocks 30 may engage.

Arms 35^a and 35^b are pivotally mounted at their lower ends on the adjustable blocks 30 and

intermediate of their ends are provided with slots 36 into which pins 37 from the see-saw board 11 extend. These pins 37 pass through said slots 36, when the see-saw board is rocked, 5 causing the arms 35^a and 35^b to swing backwards and forwards. Cords 38^a and 38^b are connected with the arms 35^a and 35^b respectively and are wound in opposite directions upon drums 39 which are freely rotative on the hollow shaft 20. 10 Adjacent each drum 39 there is a ratchet wheel 40 keyed to the hollow shaft 20 and is engaged by a pawl 41 mounted on the drum. The arrangement is such that when the drum is turned in one direction the ratchet 41 will idle on the ratchet wheel, but when turned in the other direction rotations will be transmitted to the hollow shaft 20.

The stationary shaft 21 passes through an elongated opening 43 in the see-saw board 11 so as 20 not to interfere with the rocking of the board. The shaft 21 is provided with a bottom flange 21^a fixedly mounted on the partition 31 so that the shaft 21 is fixedly supported. Intermediate of its ends the shaft 21 is provided with a flange 25 portion 21^b which is adapted to support the drums 39 forming a thrust bearing.

The operation of the device is as follows:— Children may sit on the ends of the see-saw board 11, on the seats 15, in the customary see-saw fashion and operate the see-saw by causing it to rock up and down. This rocking motion is transmitted by the pins 37 engaging the slots 36 in the arms 35^a and 35^c causing the arms to swing inwards and outwards. Since each pair 35 of arms 35^a and 35^b is connected with cords 38^a and 38^b respectively, wound in opposite directions on the drum 39, the drum 39 will be caused to rotate first in one direction and then in the other direction as the see-saw rocks.

40 The device is constructed with two drums 39 and each of these drums is driven by a pair of arms 35^a, 35^b. The operation of the drums 39 will be transmitted in one direction only by the ratchet and pawls to drive the hollow shaft in 45 one direction, which in turn rotates the annular member 17^a in one direction and causes the figures 27^a, 27^b, etc., mounted on the annular member to move around and around with the annular member.

50 To change the speed with which these figures move around it is merely necessary to loosen the clamp screws 33 and shift the blocks 30 to different positions. This will change the inclinations of the arms 35^a and 35^b and will change 55 the amplitude through which these arms are moved by the pins 37.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I 65 claim as new, and desire to secure by United States Letters Patent is:—

1. A twin rocker and rotary toy device comprising a body for supporting a see-saw board, a see-saw board pivotally mounted on said body, blocks 70 adjustably mounted on said body longitudinally of said board, arms pivotally mounted on said blocks and extending upwards and formed with slots extending longitudinally thereof, pins mounted on said see-saw board and engaging 75 said slots to swing said arms as the said board

is rocked, a rotary device mounted on said body and having a drive shaft, drums rotative on said shaft, and ratchets associated with said drums and shaft for driving said shaft in one direction as said drums swing.

2. A twin rocker and rotary toy device comprising a body for supporting a see-saw board, a see-saw board pivotally mounted on said body, blocks adjustably mounted on said body longitudinally of said board, arms pivotally mounted 10 on said blocks and extending upwards and formed with slots extending longitudinally thereof, pins mounted on said see-saw board and engaging said slots to swing said arms as the said board is rocked, a rotary device mounted on said body 15 and having a drive shaft, drums rotative on said shaft, and ratchets associated with said drums and shaft for driving said shaft in one direction as said drums swing, said blocks being mounted upon a partition within said body, clamp 20 screws projecting from said blocks and engaging through slots in said partition for holding said blocks adjusted.

3. A twin rocker and rotary toy device comprising a body for supporting a see-saw board, 25 a see-saw board pivotally mounted on said body, blocks adjustably mounted on said body longitudinally of said board, arms pivotally mounted on said blocks and extending upwards and formed with slots extending longitudinally thereof, pins 30 mounted on said see-saw board and engaging said slots to swing said arms as the said board is rocked, a rotary device mounted on said body and having a drive shaft, drums rotative on said shaft, and ratchets associated with said drums 35 and shaft for driving said shaft in one direction as said drums swing, said rotary device comprising an annular member supported by spokes connected with a common hub mounted on said drive shaft.

4. A twin rocker and rotary toy device comprising a body for supporting a see-saw board, a see-saw board pivotally mounted on said body, blocks adjustably mounted on said body longitudinally of said board, arms pivotally mounted 45 on said blocks and extending upwards and formed with slots extending longitudinally thereof, pins mounted on said see-saw board and engaging said slots to swing said arms as the said board is rocked, a rotary device mounted on said 50 body and having a drive shaft, drums rotative on said shaft, and ratchets associated with said drums and shaft for driving said shaft in one direction as said drums swing, said rotary device comprising an annular member supported by 55 spokes connected with a common hub mounted on said drive shaft, said drive shaft being hollow and rotatively mounted on a fixed solid shaft.

5. A twin rocker and rotary toy device comprising a body for supporting a see-saw board, a see-saw board pivotally mounted on said body, blocks adjustably mounted on said body longitudinally of said board, arms pivotally mounted 60 on said blocks and extending upwards and formed with slots extending longitudinally thereof, pins mounted on said see-saw board and engaging said slots to swing said arms as the said board is rocked, a rotary device mounted on said body and having a drive shaft, drums rotative on said shaft, and ratchets associated with said 65 drums and shaft for driving said shaft in one direction as said drums swing, said rotary device comprising an annular member supported by 70 spokes connected with a common hub 75

mounted on said drive shaft, said drive shaft being hollow and rotatively mounted on a fixed solid shaft, said solid shaft being fixedly mounted on a partition mounted within said body.

- 5 6. A twin rocker and rotary toy device comprising a body for supporting a see-saw board, a see-saw board pivotally mounted on said body, blocks adjustably mounted on said body longitudinally of said board, arms pivotally mounted 10 on said blocks and extending upwards and formed with slots extending longitudinally

thereof, pins mounted on said see-saw board and engaging said slots to swing said arms as the said body is rocked, a rotary device mounted on said body and having a drive shaft, drums rotative on said shaft, ratchets associated with 5 said drums and shaft for driving said shaft in one direction as said drums swing, said arms being arranged in opposite pairs, cords connected to said pairs of arms and to said drums and wound in opposite directions on said drums. 10
